Attorney

UNITED STATES PATENT OFFICE.

AIMEE DE STOOP, OF ABERDEEN, WASHINGTON.

SUSPENSION HOOK.

Application filed September 26, 1927. Serial No. 222,055.

The present invention relates to an article of manufacture, particularly designed for use by campers, tourists, soldiers and the like, and it has more particular reference to an article suspension device which is characterized by a novel arrangement of details adapting it for numerous purposes.

More specifically, I propose a product of this class possessing exclusive and distinguishing features which cooperate in a manner to provide a handy contrivance for convenient use by campers and the like, in suspending articles of clothing, cooking utensils, and so on, from make-shift supports such as fence posts, trees and the like.

The particular structural elements which go to make up this unique article will become more readily apparent from the following description and drawings.

20 In the drawings:—

Figure 1 is a side view in section and elevation, showing the improved device.

Fig. 2 is a front view of the same.

Fig. 3 is an enlarged fragmentary section 25 taken approximately upon the line 3—3 of Fig. 2.

Referring now to the drawings by numerals, it will be seen that the reference character 4 designates generally, the hook which 30 includes a suspension bill 5 and a shank 6. The shank 6 is equipped with a pair of spaced parallel arms 7 of a width slightly less than the diameter of the shank 6. This provides a shoulder at the point 8, for a purpose to be 35 hereinafter described.

Pivottally mounted between the free end portions of the arms 7 is an anchoring member which comprises a pin 9 having a pointed end 10. This pin is pivotally connected as at 40 11 between its ends to the arms. At the outer end the pin is equipped with a ring 12 and as shown in Figs. 2 and 3, the ring is formed with an inwardly extending lip 13. The pointed end 10 of the pin is adapted to swing 45 between the arms 12 allowing the arms to operate as a guard for a sheath.

Incidentally, a collar 14 is slidably mounted on these arms and normally occupies the full line position shown in Fig. 1, to cover

the point 10. This collar however, which has 50 a friction fit, is capable of movement downwardly to the dotted line position also shown in Fig. 1, in which position the point 10 may clear it, to permit the pin to be swung around to the dotted line position shown in Fig. 1. 55

As before intimated, the device is especially constructed for use by persons on camping trips, and that it may be conveniently carried in a tool box, or packed. It is advantageous in that the pointed pin 9 can be swung 60 around to the angular position shown in Fig. 1, after moving the collar 14 downwardly, to the dotted line position, whereupon the point can be forced into the trunk of a tree, a fence pole, or other wooden support. 65

This then disposes the suspension hook 4 in a position to adapt it for hanging articles of clothing, or to operate as a hat rack. The ring 10 operates as a finger ring, and can also be used as a hanger. In addition the 70 presence of the lip 13 permits the ring to have the additional function of a bottle opener. These and other advantages and features of the invention will become apparent from the foregoing description and drawings, and in view of this, a more lengthy description is believed to be unnecessary. 75

Minor changes in shape, size, and rearrangement of details coming within the scope of the adjoined claim may be resorted 80 to if desired.

Having thus described my invention, what I claim as new is:—

As a new product of manufacture, a campers' implement of the class described comprising a suspension hook including a shank, a pair of spaced parallel arms carried by said shank, said arms being of a width less than the diameter of the shank to provide a shoulder at the juncture of the arms and the shank, 90 an anchoring pin pivotally mounted between said arms, and a collar slidably mounted on said arms and cooperable with the pin to operate as a retainer, and with the shoulder to limit the sliding movement in one direction. 95

In testimony whereof I affix my signature.

AIMEE DE STOOP.
